US00D721685S

(12) **United States Design Patent**
Hasbrook et al.

(10) **Patent No.:** **US D721,685 S**
(45) **Date of Patent:** **** Jan. 27, 2015**

(54) **MOBILE PHONE CASE**

(75) Inventors: **William Benjamin Hasbrook**, Tualatin, OR (US); **Sean Michael Stuck**, Portland, OR (US)

(73) Assignee: **Mophie, Inc.**, Tustin, CA (US)

(**) Term: **14 Years**

(21) Appl. No.: **29/423,032**

(22) Filed: **May 25, 2012**

(51) LOC (10) Cl. **14-03**

(52) U.S. Cl.

USPC **D14/250**

(57) **CLAIM**

The ornamental design for a mobile phone case, as shown and described.

DESCRIPTION

FIG. 1 is a front view of the mobile phone case;

FIG. 2 is a left-hand-side view of the mobile phone case;

FIG. 3 is a right-hand-side view of the mobile phone case;

FIG. 4 is a rear view of the mobile phone case;

FIG. 5 is a top view of the mobile phone case; and,

FIG. 6 is a bottom view of the mobile phone case.

The dash-dot-dash broken lines represent the boundaries of the claim design and form no part thereof. The dash-dash broken lines illustrate portions of the mobile phone case which form no part of the claimed design.

1 Claim, 6 Drawing Sheets
